UNITED STATES PATENT OFFICE.

EDWARD WALTER LUCAS AND CHARLES JAMES SAUNDERS, OF GARDEN CITY, NEW YORK.

SHOE-LACING.

1,170,296.

Specification of Letters Patent.

Patented Feb. 1, 1916.

Application filed March 26, 1915. Serial No. 17,126.

To all whom it may concern:

Be it known that we, EDWARD W. LUCAS and CHARLES J. SAUNDERS, citizens of the United States, and residents of Garden City, in the county of Nassau and State of New York, have invented a new and Improved Shoe-Lacing, of which the following is a full, clear, and exact description.

This invention relates to sport shoes such as are used by golfers and others, and it has to deal more particularly with improvements in the means for lacing the shoe, and in this regard the invention is not necessarily limited to sport shoes.

The invention has for its general objects to improve and simplify the construction of means for lacing shoes whereby the shoe can be drawn tight or loosened with great rapidity and ease and without requiring the lacing to be laced and unlaced. The shoe is provided along the edges of the front opening with studs around which the lacing is engaged in such a manner that a pull midway down the lacing and another pull at the ends of the lacing will be sufficient to draw the shoe tight around the foot.

A more specific object of the invention is the provision of a series of rivets, studs or posts along the edges of the opening of the shoe, which rivets, studs or posts are applied to the shoe upper and to strips of leather or other material fastened thereto in such a manner that a neat and attractive appearance is obtained, and at the same time the lacing is effectively kept in laced condition.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views, Figure 1 is a perspective view of the shoe with the upper drawn open so as to illustrate the details of construction; Fig. 2 is a horizontal section on the line 2—2, Fig. 1, before the shoe is drawn closed; Fig. 3 is a sectional view on the line 3—3, Fig. 1; Fig. 4 is a detail sectional view through one of the studs or posts; Fig. 5

is a sectional view on the line 5—5, Fig. 1; Fig. 6 is a sectional view on the line 6—6, Fig. 1; and Fig. 7 is a sectional view on the line 7—7, Fig. 1.

In the present instance the invention is shown applied to a high shoe, but it is to be understood that it may be applied to a low shoe as well.

Referring to the drawing, A designates a shoe of any approved construction of the laced type, and the front edges of the upper are adapted to be drawn together by a shoe lacing 1, preferably, although not necessarily, of the round type. This lacing is engaged with spaced studs, posts or rivets 2 arranged along the front edges of the upper, and, as shown in Fig. 1, the shoe can be opened by simply slackening or loosening the lacing and pulling the upper open, the lacing freely sliding on the posts 2. In tightening the shoe it is merely necessary to pull on the lacing about midway of the shoe, say at the point 3, by engaging a finger with the portions of the lacing where they cross at the point 3, and pulling upwardly thereon, and then the free ends of the lacing are grasped to tighten the shoe above the said point by pulling upwardly on the lacing ends, and then such lacing ends are tied into a bow. It will thus be seen that with this arrangement the shoe can be quickly put on or taken off, which is a feature especially desired by golfers and others indulging in sport pastimes.

Stitched along the edges 4 and 5 of the shoe upper are strips of leather or other material 6 and 7, respectively, one of the strips forming the tongue 8 of the shoe, and fastened to these strips are the posts 2. These posts are also fastened to doubled strips of leather or other material 9 and 10 secured to the strips 6 and 7, respectively. The posts 2 are riveted to the strips 9 and 10 before the same are doubled, and after they are doubled they are held in this folded condition by a row of stitching 11 located at the side of the posts opposite to the line of fold 12. These strips 9 and 10 conceal the outer ends of the posts and give a neat and attractive appearance to the shoe. The strips 8 and 9 are secured at spaced points to the strips 6 and 7, respectively, by stitching 13, these points of stitching 13 lying midway between adjacent posts 2 and beyond the upper and lowermost posts. By

stitching the strips 9 and 10 in this manner the lacing of the shoe is facilitated, since the lacing tips can be inserted under the said strips at points between the posts 2, 5 and the points of attachment 13, both in threading the lacing outwardly and inwardly; that is to say, in applying the lacing a tip is passed under a covering strip 9 or 10 at a point under a post 2, the insertion 10 proceeding from the folded edge 12 to the other edge 12', and then the lacing is drawn outwardly in a direction away from the shoe to the desired extent, and then the tip is inserted under the cover strip 15 from the outer edge and passed over the same post 2. Next the lacing tip is crossed over to the opposite edge of the shoe and inserted under the other cover strip and below the next higher post 2, after which 20 the lacing is turned back and inserted under the same cover strip and above the same post, and in this manner the lacing is threaded back and forth, and after being once completely laced it is unnecessary to 25 disengage the lacing from the posts.

The posts are constructed as shown in Fig. 4, and each consists of an approximately double conical portion 14 having rivet shanks 15 and 16 that pierce the strips 30 6 and 9 or 7 and 10, and the rivet shanks are upset into washers 17 if such are desired. By making the bodies of the posts tapering from the ends to the middle the lacing is kept central and free movement of the 35 lacing on the posts is insured.

From the foregoing description taken in connection with the accompanying drawing, the advantages of the construction and method of operation will be readily understood by those skilled in the art to which 40 the invention appertains, and while we have

described the principle of operation, together with the device which we now consider to be the best embodiment thereof, we desire to have it understood that the device 45 shown is merely illustrative and that such changes may be made when desired as fall within the scope of the appended claims.

Having thus described our invention, we claim as new and desire to secure by Letters Patent:

1. In a lacing device an under member and an outer member, the outer member being doubled longitudinally, spaced posts riveted to the under member and to the 55 under portion of the outer member, and the outer member being fastened to the under member at points midway between the posts and outwardly from the outermost posts, whereby twice the number of apertures as 60 there are posts will be formed between the members for the passage of a lacing.

2. In a lacing device, an under member, an outer member in the form of a strip doubled longitudinally on itself, spaced 65 posts fastened to the under member and outer member, and means for fastening the edges of the doubled member to the under member at points intermediate the posts and outwardly from the outermost posts, whereby 70 openings are provided between the members for permitting a lacing to be engaged with the posts.

In testimony whereof we have signed our names to this specification in the presence 75 of two subscribing witnesses.

EDWARD WALTER LUCAS.
CHARLES JAMES SAUNDERS.
